Primary Examiner — Janice Hallmark*Assistant Examiner* — Harold E Blackwell, II(57) **CLAIM**

The ornamental design for a door stop, as shown and described.

DESCRIPTION

FIG. 1 is a perspective front view showing a new door stop in an environment of use;

FIG. 2 is a perspective back view of the door stop of FIG. 1; and,

FIG. 3 is a side view of the door stop of FIG. 1, the opposite side view being a mirror image of this side view.

The broken lines in FIGS. 1-3 illustrate portions of the door stop or environmental structure that form no part of the claimed design. The bottom of the door stop which is not shown in the drawings forms no part of the claimed design.
